UNITED STATES PATENT OFFICE.

ALBERT C. HERBERT, OF GLENLYN, VIRGINIA.

RAIL-JOINT.

947,553.

Specification of Letters Patent. Patented Jan. 25, 1910.

Application filed September 20, 1909. Serial No. 518,596.

To all whom it may concern:

Be it known that I, ALBERT C. HERBERT, a citizen of the United States, residing at Glenlyn, in the county of Giles, State of Virginia, have invented certain new and useful Improvements in Rail-Joints; and I do hereby declare the following to be a full, clear, and exact description of the invention, such as will enable others skilled in the art 10 to which it appertains to make and use the same.

The invention relates to rail joints and more particularly to the class of rail connections for joining together the meeting ends 15 of railway rails.

The primary object of the invention is the provision of a rail joint in which the meeting ends of railway rails may be joined without the necessity of the usual well known bolt fastenings which are employed 20 for connecting the fish plates in position upon the rails.

Another object of the invention is the provision of a rail connection in which the rail 25 ends will be securely united or held connected so as to form a tight joint at the meeting ends of the rails without any possibility of the separation thereof.

A still further object of the invention is 30 the provision of a rail joint in which the meeting ends of railway rails may be quickly and securely joined together without the necessity of using bolts and nuts generally employed in securing the adjacent ends of 35 the rails.

A still further object of the invention is 40 the provision of a rail joint which is simple in construction strong, durable, thoroughly reliable and efficient in operation and that is inexpensive in the manufacture.

With these and other objects in view the invention consists in the construction, combination and arrangement of parts as will be hereinafter more fully described, illustrated 45 in the accompanying drawings disclosing the preferred form of embodiment of the invention and as pointed out in the claim hereunto appended.

In the drawings: Figure 1 is a fragmentary top plan view of the meeting ends of

railway rails with the invention applied thereto. Fig. 2 is a side elevation thereof. Fig. 3 is a transverse sectional view.

Similar reference characters indicate corresponding parts through the several views 55 in the drawings.

Referring to the drawings by numerals, 5 and 6 designate generally the adjacent or meeting ends of railway rails which are of the usual well known construction, each 60 having a tread 7, web 8 and base 9, the latter resting in the ordinary manner upon cross ties 10 of the usual type. These rails in their webs have the usual bolt receiving holes or openings and on opposite sides of 65 the said rails are disposed fish plates 11 and 12, the fish plate 11 being formed at intervals on its inner face with integral hollow cylindrical protuberances or lugs 13 which project through the holes or openings in 70 the webs of the rails and receive integral pins 14 on the fish plate 12 at the opposite sides of the rails.

The lugs 13 and pins 14 contain transverse alining openings registering with each 75 other when the pins 14 have been inserted in the hollow lugs to receive a locking rod 15, the latter formed at one end with an eye terminal 16, while its opposite end contains a slot which detachably receives a key 80 17 to securely hold the locking rod from becoming detached when securing the fish plates together for joining the meeting ends of the railway rails. It being understood of course that the key 17, is inserted in the 85 rod 15, subsequent to the mounting of the same in the transverse openings contained in the interfitting lugs and pins 13 and 14 integral with the fish plates.

Various slight modifications and changes 90 may be made in the details of construction without departing from the spirit of the invention. Therefore I do not wish to confine myself to the exact construction, shown and described but wish to claim all such 95 modified forms as will come properly within the scope of the appended claim.

What is claimed is:—

In combination with the rails having apertures in the webs thereof, fish plates dis- 100

posed on opposite sides of said rails, hollow lugs integral with and projecting from the inner face of one fish plate and passed through the apertures in the webs of the 5 rails, pins integral and projecting from the inner face of the other fish plate and engaging in the hollow lugs, and a locking pin passed transversely through the inter-

fitted lugs and pins for locking the fish plates together.

In testimony whereof, I affix my signature, in presence of two witnesses.

ALBERT C. HERBERT.
